(57) **CLAIM**

The ornamental design for an electronic device as shown and described.

DESCRIPTION

FIG. 1 is a top rear perspective view of an electronic device showing our new design;

FIG. 2 is a bottom front perspective view thereof;

FIG. 3 is a rear elevational view thereof;

FIG. 4 is a front elevational view thereof;

FIG. 5 is a left-side elevational view thereof;

FIG. 6 is a right-side elevational view thereof;

FIG. 7 is a top plan view thereof; and,

FIG. 8 is a bottom plan view thereof.

The subject matter includes an electronic device in an illuminated state. The gray stipple shading depicts the illuminated region, which forms part of the claimed design. The gray stipple shading itself does not depict surface ornamentation and does not claim a particular color. All broken lines represent portions of the electronic device, which form no part of the claimed design.
